SNOWSHOE

Anson Berry, Northfield, Maine; Iva L. Berry administrator of said Anson Berry, deceased

Application May 12, 1936, Serial No. 79,383

1 Claim. (Cl. 36—4.5)

This invention appertains to new and useful improvements in snowshoes, and more particularly to a novel fastening means between the shoe and the foot of the wearer.

5 The principal object of the present invention is to provide foot attaching means for the snowshoes whereby complete freedom of movement of the foot can be had, while at the same time affording a firm connection of the foot to the shoe without likelihood of causing any resistance to the blood circulation of the wearer.

These and various other important objects of the invention will become apparent to the reader of the following specification.

15 In the drawings:

Figure 1 represents a top plan view of the improved snowshoe;

Figure 2 represents an enlarged section on line 2—2 of Figure 1;

20 Figure 3 is a perspective view of the foot engaging frame;

Figure 4 represents a perspective view of one of the frame attaching members;

25 Figure 5 is an enlarged section on line 5—5 of Figure 1;

Figure 6 is a bottom plan view of the connector shown in Figure 4.

Referring to the drawings wherein like numerals designate like parts, it can be seen that numeral 5 represents the frame of the snowshoe. This frame is one continuous piece of pliable wood having its ends secured together as at 6. Numeral 7 represents the mesh work of the shoe, this mesh work extending forwardly from the cross-member 8 and rearwardly from the cross-member 9.

A pair of connectors such as is generally referred to by numeral 10 in Figure 4, are employed and span the cross-members 8—9 as in Figure 1. Each of these connectors consists of an elongated metallic member 11 having its forward end bent backwardly under itself to form a loop 12 engaging around the cross-member 8 and further extending rearwardly to engage with the detent at 13. The opposite end of the elongated member 11 is provided with a tongue 14 which is bent under itself and also under the cross-member 9 and then forwardly where a downwardly struck out lip engages under the

tongue to retain the tongue embracing the cross-member 9.

Numeral 16 represents the U-shaped rigid frame for engaging at its slightly offset back portion 17 the rear of the foot just above the heel and at its free ends is provided with loops 18 through which pin members 19 extend for pivotally connecting the ends of the frame to the connectors 10 between the upstanding parallel flanges at 20—20. These flanges 20—20 are provided with openings 21 at longitudinally spaced intervals so that the pins 19 can be disposed through any pair of these openings depending upon the adjustment desired. The loops 18 are formed by strap iron members 22 nailed 15 or otherwise secured as at 23 to the end portions of the frame 16.

The leg portions of the frame 16 are provided with downwardly extending slots 24—24 through which a strap member 25 is disposed and this 20 strap member is adapted to engage under the instep of the wearer's foot. A second strap 26 is disposed through the horizontal slot at 27 in the end portions of the frame 16 and this strap engages over the toe portion of the wearer's foot. 25

Obviously, a foot engaging structure such as this will afford complete freedom of movement of the wearer's foot without affecting the firm connection of the snowshoe to the wearer's foot.

While the foregoing specification sets forth 30 the invention in specific terms, it is to be understood that numerous changes in the shape, size, and materials may be resorted to without departing from the spirit and scope of the invention as claimed hereinafter.

Having described the invention, what is 35 claimed as new is:

In a snowshoe construction, a pair of shoe attached channeled members, a substantially U-shaped frame against which the heel of the 40 wearer's shoe can engage, said U-shaped member being provided with transverse loops at their free ends disposed into the channeled members and pins disposed through the channeled members and through the said loops, for swingably 45 connecting the U-shaped member to the channeled members, each of the said channeled members being provided with a forwardly extending shoe strut embracing strap.

ANSON BERRY. 50
